UNITED STATES PATENT OFFICE.

JOHN H. CRESWELL, OF PEROTE, ALABAMA.

MAIL-BOX SUPPORT.

1,215,915.

Specification of Letters Patent. Patented Feb. 13, 1917.

Application filed June 15, 1915. Serial No. 34,258.

To all whom it may concern:

Be it known that I, JOHN H. CRESWELL, a citizen of the United States, residing at Perote, in the county of Bullock and State of Alabama, have invented certain new and useful Improvements in Mail-Box Supports, of which the following is a specification, reference being had to the accompanying drawings.

10 This invention relates to an improved mail box support and has for its primary object to provide means for securely supporting a mail box such as is commonly used upon rural routes, in position upon a post or standard.

15 The invention has for an additional object to provide a support of the above character embodying a vertical post or standard, a horizontally extending arm vertically adjustable at one end upon the post, and means carried by said arm for securely clamping a mail box in position thereon.

20 It is an additional general object of the invention to provide a device of the above character which is exceedingly simple in its construction, may be manufactured at comparatively small cost, and can be readily set up in position for use and properly adjusted by the carrier to suit his convenience.

25 30 With the above and other objects in view, my invention consists in the novel features of construction, combination and arrangement of parts to be hereinafter more fully described, claimed, and illustrated in the accompanying drawings, in which,

Figure 1 is a perspective view showing my improved mail box support;

Fig. 2 is a transverse section;

Fig. 3 is a detail perspective view of the 35 box supporting arm.

Referring in detail to the drawing and more particularly to Figs. 1 and 2 thereof, 5 designates the post or standard which is preferably formed of galvanized metal pipe and is of sufficient length to permit the lower end portion thereof to be embedded in the ground while the major portion of the post extends above the ground surface.

6 designates the box supporting arm, one 40 end of which is enlarged and provided with an opening indicated at 7, to loosely receive the post or standard 5. This enlarged end of the arm 6 carries a set screw 8 which is adapted to be adjusted into binding en-

gagement against the post 5 to retain the 55 horizontal arm 6 in its adjusted position upon the post.

B indicates the mail box which is adapted to be arranged upon the supporting arm 6, and in Fig. 1 of the drawing, I have shown 60 this box provided with a hinged end door. In securing this type of mail box upon the supporting arm, I employ the two confronting spring clamping plates 9 which are formed with straight end portions 10 extending across the upper surface of the arm 6 and superposed upon each other. Each of these spring clamping plates is provided with a series of spaced openings 11 which are adapted to receive the bolt 12 extending 70 through the outer end of the arm 6. A nut 13 is threaded upon the lower end of this bolt for clamping engagement against the under side of the arm, whereby the spring plates 9 are held in their adjusted positions. 75 The outer end portions of the plates 9 are upwardly and inwardly curved or bowed, and have their terminals reversely bent, as at 14, for clamping engagement against the opposite side walls of the mail box B. It 80 will be readily understood that the clamping plates 9 may be readily adjusted with respect to each other transversely upon the arm 6, in accordance with the size or width of the mail box B which is to be received 85 between the opposed free ends of said clamping plates. These plates act to securely clamp the box in position upon the arm 6 and hold the same against casual displacement. The carrier may open the end 90 door of the box and place the mail therein without descending from his vehicle, and he may readily adjust the box to the proper height by simply loosening the set screw 8 and shifting the arm 6 vertically upon the 95 post or standard 5. It is to be observed that the free extremity of one of the end portions 10 is offset, as illustrated in Fig. 2, in order to afford the requisite coaction with the second straight portion 10 and as is 100 illustrated in this figure; it is also to be noted that the portions 10 are seated within the groove 6^a formed in the upper face of the arm 6 adjacent the outer end thereof and extending entirely thereacross. The 105 portions 10 are adapted to be seated within this groove 6^a whereby it will be perceived that the spring plates 9 are held against

rotatable movement around the bolt 12. Furthermore it is to be noted that the groove 6^a is of such a depth as to prevent the end portions 10 extending above the 5 upper surface of the arm A and thereby offering no obstruction to the proper seating of the box B. The arm 6 is provided at its transverse center with an opening 12^a in communication with the groove 6^a and 10 through which the bolt 12 is adapted to be loosely directed with the head of the bolt uppermost and also below the upper surface of the arm 6, the depth of the groove 6^a allowing for this additional thickness.

15 From the foregoing description, taken in connection with the accompanying drawing, the construction, manner of use and several advantages of my invention will be clearly understood. It will be seen that I have devised a very simple support and clamp for 20 rural mail boxes which is of great convenience in that it enables the box to be readily placed in position or removed from the supporting arm, and the carrier may also adjust the box to the desired height above the ground so that he may place the mail therein without descending from the vehicle. The device is also very durable and, in view 25 of the few parts employed and their very simple form, it is obvious that the support can be manufactured and sold at relatively small cost.

While I have shown and described the preferred construction and arrangement of 30 the several elements employed, it is to be understood that the device is susceptible of considerable modification therein and I, therefore, reserve the privilege of resorting to all such legitimate changes as may be

fairly embodied within the spirit and scope 40 of the invention as claimed.

Having thus fully described my invention, what I desire to claim and secure by Letters Patent is:—

A mail box support including a post or 45 standard, a horizontally disposed arm vertically adjustable upon said standard, means for securing the arm in its adjusted position, said arm being provided in its upper surface adjacent one end with a transverse 50 groove and with an opening at its transverse center in communication with the groove, spring clamping members engaged at one of their ends in said groove and lapping upon each other, each of said members 55 having a plurality of openings, a vertically disposed bolt loosely disposed through the opening in said arm and disposed through coinciding openings in the clamping members with the head thereof uppermost, a 60 clamping member threaded upon the lower end of the bolt and coacting with the under surface of the arm to secure the spring clamping members in operative relation, and a mail box adapted to be disposed upon 65 the arm over the groove therein, said box being engaged and held in position by the opposed clamping members, the groove of the arm being of a depth less than the combined thicknesses of the overlapping portions of the spring clamping members and the head of the bolt coacting therewith.

In testimony whereof I hereunto affix my signature in the presence of two witnesses.

JOHN H. CRESWELL.
